BED-SPRING TIGHTENER.

No. 807,348.

Specification of Letters Patent.

Patented Dec. 12, 1905.

Application filed July 15, 1905. Serial No. 269,767.

To all whom it may concern:

Be it known that I, ALBERT L. BARNUM, a citizen of the United States of America, residing at Pineridge, in the county of Shannon and 5 State of South Dakota, have invented new and useful Improvements in Bed-Spring Tighteners, of which the following is a specification.

This invention relates to improvements in bed-spring tighteners, and has for its object 10 to provide a simple and effective construction of tightening device whereby the spring of a bed may be conveniently adjusted to the desired tension.

Another object is to provide a tightener 15 whereby the portions of the spring on opposite sides of the center line of a bedstead may be tightened to different degrees according to the weight which is to be sustained thereby.

The preferred embodiment of the invention 20 is illustrated in the accompanying drawings, in which—

Figure 1 is a top plan view showing the application of the tightener to the side rails of a bed-spring frame, one of the movable members being broken away to better expose the 25 interior construction. Fig. 2 is a section on the line 22 of Fig. 1. Fig. 3 is a cross-section through the tightener, showing one of the tightening-rolls held by the dog and illustrating 30 in full and broken lines the adjustability of the dog. Fig. 4 is a perspective view of the frame-bar or stationary member of the tightener detached from the spring-frame. Fig. 5 is a perspective view of one of the dogs, 35 and Fig. 6 is a similar view of one of the end disks or heads.

Referring now more particularly to the drawings, the numeral 1 represents the stationary member of the tightener, which in 40 practice extends transversely of the bed-spring frame and forms one of the end pieces or rails thereof to connect the adjacent ends of the side pieces of said frame. As shown, the member 1 is in the form of a winged bar 45 and comprises a horizontal body-plate 2, provided with a depending strengthening-flange 3, coextensive in length with the plate. The ends of the plate 2 are apertured, as shown at 4, for the passage of screws or other suitable fastenings 5 to secure the same to the

ends of the side rails 6 of the spring-frame. The ends of the flange 3, underlying the perforated ends of the plate 2, form tongues 7 to engage slots 8, formed in the rails 6 to provide a rigid connection supplementing the 55 holding action of the screws 5 to rigidly connect the stationary member to the frame. The plate 2 is also provided with a vertical flange 9, which is connected with the outer flange or portion of the horizontal plate 2 by 60 a series of webs or ribs 10, said webs or ribs being arranged in spaced pairs to form a series of chambers or pockets 11.

Revolutely mounted upon the member 1 is a series of movable members 12, each consisting of a cylindrical roll or sleeve surrounding the member 1 and adapted to turn upon the radial wings thereof. The rolls or sleeves 12 are coextensive in length with the distance between the pockets 10 and are arranged so 70 that they break joint with or overlap said pockets with their ends terminating between the pockets. In other words, each roll or sleeve centrally incloses one of the pockets and has its end portions terminating midway 75 of the distance between said pocket and the next adjoining pockets, the rolls or sleeves thus inclosing the bar between the rails 6. The outer ends of the outer sleeves are closed by disks or heads 13, which abut against the 80 inner faces of the rails 6 and protect the same from wear, each of which is provided with a cruciform slot 14 to adapt it to be fitted upon the tongue 7 and apertured end of the plate 2. Each roll or sleeve 12 is provided with a holding bar or member 15 to engage and clamp the end of the spring 16, said bar being secured thereto by screws 17. Each bar 15 in addition to forming a clamp for the end of the spring provides a shoulder with which a suitable implement may be engaged to turn the roll to tighten the spring to the desired tension. 85

Arranged within each pocket 10 is a locking-dog 18, each dog being, like the pocket, 90 of segmental form and having a straight bearing edge 19 to normally rest against the flange 9 and a curved or rounded base 20, on which it is adapted to tilt or rock on the outer flange or portion of the plate 2, and a biting tooth 100

or edge 21, formed at the intersection of the fulcrum edge 12 with the edge 22 of the dog opposite the inner or bearing edge 19.

The inner flange or portion of the horizontal plate 2 is of somewhat greater width than the outer edge or portion of said plate, the flanges 3 and 9, in order that each roll or sleeve 12 may bear when in locked position against the edge of the said inner flange or portion of the plate 2, as shown in Fig. 3, to supplement the action of the dog to hold the roll from retrograde rotation under the pull of the tightened spring 16. The dogs 18 normally stand in the position shown in Fig. 3, from which it will be seen that their bearing edges or abutting portions 19 rest against the flange 9, while their teeth 21 engage the inner periphery of the rolls 12 and hold the same from retrograde rotation or motion to the left in Fig. 1 under the pull of the spring 16, while permitting the rolls to be turned to the right in Fig. 1 to tighten up the spring, such motion of the rolls being permitted by the capability of the dogs to turn upon their fulcrums 20 to the dotted-line position shown in Fig. 3. It will thus be understood that after the spring has been adjusted to the approximate tension it may be tightened to the exact tension desired by applying an adjusting-tool to each roll and turning the same outwardly or to the right, the dogs 18 tilting outwardly on their fulcrum portions 20 to accommodate such movement and arresting the movement when the outer edges of their said fulcrum portions abut against the plate 2 and their apex portions come into contact with the inner peripheries of the rolls, as indicated in dotted lines in Fig. 3. The tooth or biting edge 21 of each dog will remain in contact with the roll and hold the same from retrograde rotation in its newly-adjusted position. It will of course be understood that by properly shaping the dogs the rolls may be given different degrees of adjustment, so that the different portions of the spring lying on opposite sides of the longitudinal center of the bedstead may be tightened to different degrees, according to the weight which is to be sustained thereby.

From the foregoing description, taken in connection with the accompanying drawings, the construction and mode of use of my improved spring-tightener will be apparent, and it will be readily seen that the invention provides a device of this character which forms an element of the spring-frame which is strong and durable and adapted to permit the spring to be conveniently tightened, which forms a permanent fixture of the spring-frame, and in which the locking elements are concealed and protected. By thus inclosing the locking elements the entrance of dust and

moisture will be prevented, so that they will at all times be free for movement to permit the tension of the spring to be regulated. As 65 the spring stretches in use the dogs may be set for tightening the same to a further degree by removing the stationary element 1 and detaching one of the rolls therefrom, after which the other sleeves may be adjusted to permit 70 the dogs to be reset to their normal position, so that when the rolls are reapplied and the stationary member again fixed to the spring-frame the parts may be adjusted in the manner before described to tighten up the spring. 75

Having thus described the invention, what is claimed as new is—

1. A bed-spring tightener comprising a stationary member provided with a series of chambers or pockets, a series of rolls adapted 80 to turn upon said stationary member, and dogs disposed in said pockets and adapted to engage the rolls to hold the same from retrograde rotation, said dogs being adapted to tilt to permit the rolls to be turned in one direction for 85 tightening a spring.

2. A bed-spring tightener comprising a stationary member composed of a bar provided with means of attachment to the side rails of a spring-frame and having a series of pockets, 90 a series of rolls mounted to turn upon said bar, disks or heads mounted upon the ends of the bars and closing the outer ends of the outer rolls, and dogs in said pockets to engage and hold the rolls from retrograde rotation, 95 said dogs being adapted to tilt to permit adjustment of said rolls in one direction, whereby the rolls may be independently adjusted to tighten the spring.

3. A bed-spring tightener comprising a stationary member provided with a pocket having walls arranged approximately at right angles to each other, a roll adapted to turn upon the stationary member, and a segmental dog disposed loosely in said pocket, said dog having a straight bearing edge adapted to rest against one of said walls, a rocking edge adapted to rest upon the other wall, and an abutting tooth to engage and hold the roll from retrograde movement, the construction being 100 such that when the roll is turned forwardly the dog will tilt upon its rocking edge to accommodate such movement and adapt the roll to be turned forwardly to the desired extent, whereby upon a prescribed retrograde movement of the roll the dog will swing back to locking position to hold the roll from further retrograde movement.

4. A bed-spring tightener comprising a stationary member provided with a series of chambers or pockets, a series of rolls adapted to turn upon said stationary member, each of said pockets having walls arranged substantially at right angles to each other, and seg-

mental dogs loosely disposed in said pockets, each of said dogs having a bearing edge to engage one of the walls, a fulcrum edge to tilt upon the other wall, and an abutting tooth to engage the roll, whereby when the roll is turned forwardly the dog will tilt upon its fulcrum edge to accommodate such movement and permit the roll to be adjusted as desired, and upon the prescribed retrograde movement

of the roll the dog will swing back to locking position to hold the dog from further retrograde movement.

In testimony whereof I affix my signature in presence of two witnesses.
